UNITED STATES PATENT OFFICE.

ALBERT F. NATHAN, JR., OF NEW YORK, N. Y.

TYPE-WRITER KEY-LOCK

1,137,417.

Specification of Letters Patent. Patented Apr. 27, 1915.

Application filed September 7, 1905. Serial No. 277,297.

To all whom it may concern:

Be it known that I, ALBERT F. NATHAN, Jr., a citizen of the United States, residing in the city of New York, in the county of New York and State of New York, have invented a certain new and useful Type-Writer Key-Lock, of which the following is a specification.

This invention relates broadly to mechanism for automatically locking some or all of the keys of a typewriter, but, in its more intense aspect it particularly concerns a line-lock in which a finger-key is instrumental in directly enabling or effectuating a movement of the line-lock into locking or operative position. Since, however, certain advantages characteristic of this invention prominently appear when it is resorted to for the purpose of enabling a dividing-key 10 to lock the remaining keys against depression at any time after the carriage has traveled beyond a pre-determined adjustable station of its travel, it will be conducive to clearness to disclose the invention through 15 certain possible concrete embodiments in such relation.

Heretofore, the carriage of a typewriter has in and of itself directly thrown the line-locking mechanism into locking or operative 20 position, and while such carriage has been in turn controlled in its travel by a finger-key such key has never heretofore been in any way instrumental in causing or enabling the line locking mechanism to move into locking or operative position, save only by 25 enabling the carriage to travel until such carriage directly throws the line-lock, *i. e.* through the medium of the carriage. This 30 is to say, a finger-key has never heretofore been arranged to directly actuate the line locking mechanism into locking or operative 35 position, but on the contrary has always merely served to release the carriage, to enable the latter directly and in and of itself 40 to perform such function, although it is to be understood that devices for unlocking line locking mechanism as a direct consequence of a key actuation have been contemplated. The purpose of such unlocking devices, as 45 will be understood by those familiar with the art, is entirely different from that of my device and the problem to be solved and the reasons involved are radically different in each case.

Now by my invention, I seek broadly to

produce a mechanism in which a finger-key coöperates with the carriage as well as with the locking device itself for the purpose of moving the line-locking mechanism into locking or operative position, as distinguished from the heretofore constructed line locks, in which the carriage merely by traveling past a certain station itself operates and moves the line-lock to locking or operative position; the actuation of the finger-key merely serving to release and enable the carriage to travel. In other words, I propose to utilize the carriage for the purpose of first part-way operating or getting into operative relation with the line-lock, and then use a finger-key for completing the movement of the line-lock into operative position.

My invention furthermore has in view among other objects, a mechanism for permitting the operator to finish a word or syllable thereof without being interrupted by a premature locking of the keys. In carrying out this aspect of my invention, I also make provision whereby the line-lock mechanism is operated partly by the carriage and partly by a word or syllable dividing key, as for example, a so-called "space-key."

In this utilization of my invention, the carriage and dividing key coöperate to lock the printing keys and the like against actuation. Unassisted by one another, neither alone can do this, and even together are ineffective to lock the keys until the completion of the line of writing, at which point the carriage throws a part into such position that the dividing key may act thereon to interpose an obstruction into the path of the printing keys to be locked.

Other objects and advantages will be in part obvious from the annexed drawings, and in part pointed out in the following description.

In general, this invention seeks to provide a means of the nature disclosed which from a mechanical standpoint will in practical usage possess a high degree of efficiency, and which, structurally considered, will be of the greatest possible simplicity, being composed of but few parts all capable of being manufactured at a minimum of cost and so co-related as to be capable of being conveniently and compactly assembled and arranged in typewriters of a conventional character.

The invention accordingly consists of the features of construction, combinations of elements, and arrangements of parts, which will be exemplified by the embodiments hereinafter set forth and defined as to scope and application by the prior art after the manner indicated in the following claims.

In order that this invention may be the more clearly understood by others skilled in its relating arts, drawings illustrating several of the various possible applications of the same are appended as a part of this disclosure, although the controlling features of this invention may be otherwise applied by modifications obviously deducible from this disclosure and accordingly comprehend within the intended scope of the claims.

In the appended drawings, corresponding parts are similarly referred to by like characters of reference throughout all the views of which:

Figure 1 is a perspective view generally indicative of a conventional form of a typewriter and disclosing one of the many possible modes of applying my invention thereto, and more particularly illustrating an embodiment thereof wherein a depression of a finger-key, such as the shown dividing-key, during a predetermined range of the travel of the carriage, releases and enables an energized universal locking bar to spring into locking position. Fig. 2 is a perspective view of a slightly different embodiment of my invention wherein a depression of a spacing or dividing key moves a member connected therewith into operative relation with an interponent which has been previously moved by the carriage, so that a subsequent movement of the member connected with the spacing or dividing key will move the interponent into a different direction, with the result that the line-lock is brought into effective locking position. Figs. 3, 4, & 5 show successive steps in the operation of the key locking means more fully disclosed by Fig. 1. Fig. 6 is a side elevation showing elements of my invention including an alarm mechanism adapted to sound the instant the lock is moved into effective relation with the keys. Fig. 7 is a detailed perspective of a conventional model of a typewriter equipped with my invention and showing its relation with various features commonly employed in typewriters.

To more clearly appreciate the peculiar utility of the particular embodiments of this invention which have been herein illustrated, it may at the outset be pointed out that, as heretofore constructed, line locking devices have always operated at a predetermined fixed point in the line of writing. For example, the instant the carriage reaches a certain definite station near the end of the line, say space 70, the line lock becomes operative to lock the keys against

further depression, regardless of whether the operator is in the midst of writing a word. It has heretofore been necessary to meet this exigency by providing a key for releasing the lock, so that the word may be completed by the operator. As will be readily appreciated, it is a cause of great annoyance and confusion to the operator to be interrupted in the middle of a word, and this goes far toward offsetting the advantages of a line lock. 75

By means of the specific embodiments herein illustrated, it now becomes possible to overcome this difficulty and permit the operator to finish a word before a locking 80 of the keys takes place. This is done by utilizing what may be termed a sub-conscious act on the part of experienced typewriters, which consists in depressing some key adapted to space or divide words or 85 syllables from one another. Thus, at the end of every word the operator will depress a dividing key which does not print, but leaves a space or blank. Such a key may be termed a "space key." So also, in the case 90 of compound words, the key printing a hyphen will be employed in lieu of other keys, and the same is equally true of split words.

Now, in carrying out this invention, the mechanism is such that the dividing key as 95 it may be termed can be freely used during the greater length of the writing of the line without bringing about a locking of the keys, but just as soon as the carriage has passed beyond a given point, and is traveling in what may be termed the effective 100 region of locking, the dividing key will upon being depressed, instantly move or enable the line locking mechanism to move into operative position so as to lock the keys against 105 subsequent writing.

Continuing now by way of a more detailed description of the several disclosed embodiments of my invention designed to operate in the above stated manner, A indicates the paper carriage or platen of a typewriter which is moved for letter spacing in the usual manner and which receives the impact of the printing mechanism. 110

In the form denoted by Figs. 1, 3, 4, and 115 5, a cam or tappet B is mounted on the carriage and, as shown, is provided with a sloping under face adapted to enable the coacting arm of the bell-crank D to freely ride up the same, thus swinging the bell-crank D 120 into the position denoted in full lines; the normal position being indicated by the dotted lines as shown at D'.

The free or swinging arm of the bell-crank D is attached to a forwardly extending link E, attached at its forward end to the line lock mechanism. A returning spring S is so arranged as to urge the link into its normal position indicated by the dotted lines at D'. 125

At its forward end, the link E extending from the carriage tappet is pivotally attached to the arm G, which is rocked to and fro as the bell-crank D rides up and down 5 the tappet mounted on the carriage. As will be presently seen, the line lock mechanism, in the illustrated embodiments of my invention, is entirely ineffective when the link is forward in its normal position, and the 10 arm G has similarly been rocked forwardly into the normal position indicated by dotted lines at G'. On the other hand, when the link E has been moved to the rear so as to swing the arm G into the position shown by 15 the full lines, the line lock mechanism has become so affected that immediately upon depressing the dividing or spacing key K, it will swing into locking position.

The universal locking bar H is in the 20 form of an arch or bail and has a torsion spring I, which is at its ends affixed to the ends of the bail; the latter turning upon the pivot J mounted between side walls rising from the machine base.

25 The universal locking bar H when swung upwardly into locking position as indicated by the dotted lines at H², directly underlies the type-bar levers L and when so positioned, the latter obviously cannot be depressed.

When the tappet B depresses the horizontal arm of the bell-crank D, the parts are moved to the full line position shown by Figs. 1 and 4, and in so doing, the middle 30 portion of the flat torsion spring I has been twisted to a vertical position, as seen by Fig. 4. In order to prevent a premature rise of the locking bar H due to the spring tension, I have provided a latch connected with the 35 dividing key K. Such latch is indicated more clearly at K² and is preferably formed upon the space-key lever. This latch is engaged by a finger or projection H' formed upon the locking bar H. Thus, it will be 40 seen that the carriage, except for the latch K² would at once rotate the bar H to lock the keys, but that bar is restrained by the latch K². Upon depressing the space key, however, said latch released the projection 45 H' and hence the bar H springs up as a result of its turning on the pivot J, and occupies a position immediately beneath the lever L of the type-keys, (Fig. 5) so that the latter are locked against depression; the depressed position of the keys being indicated at L', Fig. 1, and the locking position of the bar or frame H being indicated at H², Figs. 1 and 5. Thus, it will be seen that the operator is always able to complete a word before the type-keys become locked, thereby 55 saving much annoyance and confusion and conducing to the speed of operation. It will be understood that the tappet B which may be adjustable longitudinally of the carriage 60 after the manner usual in line-locking de-

vices, may be set so as to operate at a point, say equal to eight letter spaces from the extreme end of the line, and it will be found in practice that the words will run from one to five letters beyond this point. The tappet 70 B, however, may be adjusted farther away from the finish of the line, according to the preference of the operator. Upon the return of the carriage, the bell crank D is released, and the parts return to their normal 75 position by the action of the spring F, the long projection or finger H' slipping over the latch K².

The above described modification of my invention discloses a construction in which 80 the carriage puts the line-locking mechanism under a tension, and the dividing key serves to release such tensioned locking mechanism, thereby enabling it to spring into locking position. The reader skilled 85 in the art will no doubt have perceived at this point that an equivalent mechanism readily deducible from the foregoing disclosure may be employed in which the movement of the finger key may be utilized as a 90 means instrumental in causing or enabling the locking features to shift into operative position after the carriage has set them so that they may be acted upon by such key.

By way of a more complete illustration of 95 this other equivalent modification of this invention, I have shown by Figs. 2 and 7, an application of my invention in which a movement of the dividing or space key operates directly to urge or force the line-locking 100 mechanism into locking position. In the shown specific embodiment, such movement is the uprise of the finger-key (space key) though of course the initial depression may serve the same purpose. Thus, in the one 105 case, the finger key releases a previously energized line-lock, while in my equivalent other modification, it pushes the line-lock into operative or effective position.

Referring now to Figs. 2 and 7 (Fig. 2 110 showing more clearly details of the engaging means between the spacing finger-key and the line lock mechanism, and Fig. 7 showing more clearly the application of this invention to a typewriter possessing the conventional details such as spacing mechanism, escapement mechanism, printing mechanism and the like) A indicates the paper carriage or platen. As shown by Fig. 7, such platen or paper carriage ordinarily comprises a 115 120 paper roller 1, a carriage frame 2, a ratchet bar 3, and antifriction rollers 4, and an adjustable tappet or cam B adapted to operate on the line locking mechanism when the carriage approaches the end of the line, and according to my invention, setting such line-locking mechanism in such relation that a depression of a finger-key, such as a space key will bring it into locking position.

This modification of my invention pro- 130

poses an interponent which is moved by the carriage into the path of a vibrating member; the movement of the latter being caused by the up and down reciprocation of a finger-key, such as a space key or dividing key. In the illustrated form of my invention, such interponent comprises a member N together with pivoted means M of Fig. 2 and M² of Fig. 7.

19. As will be seen, this pivoted means is here shown in the form of a lever which is so mounted and arranged with reference to the interponent N, that such interponent N will be moved by the carriage at least whenever the latter approaches the end of a line. As a matter of convenience, the interponent N has been brought forward so as to terminate adjacent the forward or power receiving portion of the keys.

20. The advantages of this location is that it is very near the line-lock which by engaging with the forward or power receiving portion of the keys acts at the most effective position. The interponent or slide N projects 25 through a loose fitting opening in the comb O, the latter being supported by means of pins or projections O' in the side walls rising from the base, so that the comb may slide transversely beneath the levers L. It is 30 to be noted in this connection, that this arrangement gives the interponent two independent movements at right angles to each other. That is to say, the interponent moves backwardly and forwardly across the path 35 of a member P which vibrates in correspondence with the depressions of the finger key K.

Considering now the manner in which this transverse shifting of the locking device is obtained, P denotes an arm of a bell-crank 40 pivotally mounted on pivots P', which bell crank also has an arm P² which is pivoted to the finger-key lever K. This pivotal connection may be very conveniently attained 45 by providing one or the other of these members with an eye through which the other passes loosely, as shown on the drawings.

The upright arm P of the bell crank is 50 resilient or flexible in a backward or forward direction, so that the interponent N may be urged forwardly and cause such arm P to spring forwardly, so that when it is moved laterally, it will spring back at one side of the protruding portion of the interponent N. 55 Thus when the arm M or M² is thrown forward by the cam B, the front end or tongue N' of the slide or interponent N advances and presses or springs the arm P toward the front of the machine. As will be seen, this 60 will not, however, cause any shifting or other movement of the locking comb O. When subsequently the dividing or space key is depressed, a rocking movement will be imparted to the bell-crank and its arm P² will be carried down by the lever of such de-

pressed finger key, and the arm P will be vibrated to the right until it passes over the end of the protruding tongue N' and snaps back at the right of such protruding portion. Now when the finger is removed from such 70 finger key, the spring P² will operate to lift the same and the arm P of the bell-crank will be caused to vibrate toward the left, but in so doing it will abut the protruding portion of the interponent N' and force the 75 same to the left together with the comb O so that the teeth O² of the latter will be brought directly under the levers L of the other finger keys, and hence the latter will be prevented from being depressed. 80

It may here be noted, however, that should the operator desire to depress one of the keys, it will merely be necessary to move or hold down the finger key K, for this will return the lever arm P to the right, this movement being followed by a temporary return of the comb to normal position, due to the action of the spring R.

When the carriage is returned for writing a new line, the slide or interponent N will 90 be withdrawn from the part of the vibrating member P actuated by the finger key, this withdrawal being accomplished by means of the spring R. The moment the interponent is withdrawn sufficiently to disengage its 95 protruding end from the member P, the locking comb O will be able to spring back into normal effective position, so that the key levers L may pass freely down in the slots between the teeth O². 100

By Fig. 7, I have illustrated certain other features than those above described or alluded to as a part of my invention, but I do not mean to cover such features as may be well known in the art and are in common 105 use. By this I refer to the escapement mechanism indicated by 6 and operated from the universal bar 7, which in turn is depressed by the key levers through extensions 8. Such universal bar 7 may also be depressed 110 by the finger-key K through the medium of the lever arm 9. The printing type are carried at the ends 10 of the type-bars 11 operated by means of links 12, connected with the key levers. 115

Within the scope of my invention, other modifications than those specifically illustrated may be resorted to without a departure therefrom, and portions of my improvements may be used without others, thus, as 120 will be readily apparent, any of the finger keys may be connected with the mechanism forming a part of my invention.

Having thus described my invention, what I claim as new and desire to secure by Letters Patent of the United States may be stated as follows:

1. A typewriter comprising in combination, a carriage, a plurality of operating keys, a member connected with an operat- 130

- ing-key and adapted to be vibrated thereby, a member movable by said carriage into the path of said vibrating member, and a device for locking certain of said keys and 5 movable into operative position by said carriage-moved member when it is moved by said vibrating-member.
2. A typewriter comprising in combination, a carriage, a plurality of operating-keys, a vibrator movable by an operating-key, an interponent movable by said carriage into the path of said vibrator, whereby said interponent may be laterally shifted by said vibrator, and a key-locking device 10 movable into locking position by said interponent when the latter is shifted by said vibrator.
3. A typewriter comprising in combination, a carriage, operating-keys, a line-lock, 15 an operative connection between said carriage and said lock, and independent means extending from an operating-key to said line-lock adapted to enable said key to move said line-lock into locking relation with other of 20 said keys.
4. A typewriter comprising in combination, a carriage, operating-keys, a line-lock mechanism, a device movable by said carriage for rendering effective and ineffective 25 said line-lock mechanism to the action of an operating-key, and means controlled by an operating-key for coöperating with said carriage-moved means for setting said mechanism into locking relation.
5. A typewriter comprising in combination, a carriage, operating-keys, a line-lock, 30 normally ineffective line-lock operating means connected with an operating-key, a device operated by the carriage for rendering said operating-means effective after a given station has been passed by the carriage, whereby other operating-keys may be locked after the next stroke on said first 35 mentioned operating-key.
6. A typewriting machine comprising in combination, a carriage, a plurality of key-levers, a line-locking-mechanism, operative connections between the carriage and the locking-mechanism, and means directly operable by one of the key-levers to engage the 40 operative connections and move the locking-mechanism into operative position.
7. A typewriter comprising in combination, a carriage, a plurality of key-levers for printing characters composing a word, an operating-key for causing said carriage to move a space but unadapted to print any of 45 said characters, a normally-ineffective mechanism adapted to be moved into effective position to lock said key-levers, and means independent of said key-levers coöperating with said operating-key to move said mechanism into effective position when said operating-key is actuated.
8. A typewriter comprising in combina- 50
- tion, a carriage, a plurality of key-levers for printing characters composing a word, an operating-key adapted to move said carriage a space when actuated without printing any of the above-mentioned characters, 55 and means independent of said key-levers for automatically locking the same against printing when the carriage has passed a predetermined station upon actuating said operating-key, and adapted to be released by 60 depressing said operating-key.
9. A typewriter comprising in combination, a carriage, a plurality of key-levers for printing characters composing a word, an operating-key adapted when actuated to 65 space said carriage without printing any of said characters, and means independent of said key-levers adapted when the carriage has passed a predetermined station to co-operate with said operating-key to automatically lock said key-levers when said operating-key rises after being depressed, and adapted to be unlocked subsequently by depressing said operating-key.
10. A typewriter comprising in combination, a carriage, a plurality of key-levers for printing characters composing a word, an operating key adapted when actuated to 70 space said carriage without printing any of said characters, a member located under the forward portions of said key-levers and adapted to be moved into a position preventing a depression of same, means co-operating with said operating-key and normally ineffective to move said member, and a device adapted to render said means effective at a predetermined position of the carriage.
11. A typewriter comprising in combination, a carriage, a line-lock member advanced by the carriage, a second line-lock member carried by an operating-key, printing instrumentalities, and means for automatically locking the printing instrumentalities against printing when said members are 75 brought into contact by an actuation of said operating-key.
12. A typewriter comprising in combination, a carriage, printing instrumentalities, a line-lock stop carried by the carriage, 80 means for adjusting said stop, an operating-key, a line-lock part connected with said operating-key, and means comprising a device intervening between said stop and part as well as a locking-member, adapted and arranged for automatically locking the printing instrumentalities against printing when said stop, said last-mentioned means, and part are brought into operative relation by 85 an actuation of said operating-key.
13. A typewriter comprising in combination, a carriage, a plurality of key-levers for printing characters composing a word, an operating-key adapted when actuated to 90 space said carriage without printing any of 95

2 said above mentioned characters, a locking-member located under the forward portions of said key-levers, means coacting with said member and said carriage, and a device independent of said key-levers and coöperating with said operating-key to enable the latter to move said locking-member into locking position when the carriage has passed a predetermined station of its travel.

5 14. A typewriter comprising in combination, a carriage, a part on said carriage, a line-lock member adapted to be moved by said part, means for adjusting the relation between said part and member to enable the latter to be moved when the carriage reaches any predetermined station, a plurality of key-levers, a device adapted to lock said key-levers and connected with said line-lock member in such manner that the latter may 10 be moved by the carriage without moving said device, and a piece normally free from said device and actuated by a key-lever to vibrate adjacent a portion of said line-lock member remote from said part, whereby 15 when said member is moved by said carriage said piece will be brought into engagement with said member when said key-lever is depressed through pressure exerted upon the same, and enable said piece to move said 20 member during the uprise of said key-lever and cause said device to move into locking position.

25 15. A typewriter comprising in combination, a carriage, a plurality of key-levers for printing characters composing a word, an operating-key adapted when actuated to space said carriage without printing any of said word-composing characters, a lever actuated by 30 said line-lock stop, a line-lock adapted to be moved into locking position by said lever, and means controlled by an operating-key for moving said lever to bring said line-lock 35 into locking position.

35 16. A typewriter comprising in combination, a carriage, printing instrumentalities, operating keys, a line-lock, a member coöperating with said line-lock adapted to be 40 moved by the carriage in one direction into a given position, and means actuated by an operating-key adapted to move said member in another direction when in said position, and thereby produce a movement of said 45 line-lock.

45 17. A typewriter comprising in combination, a carriage, a part carried thereby, a member adapted to be engaged and moved by said part, operating-keys, means for locking certain of said keys and coöperating 50

55 with said member, and a device directly controlled by an operating key and coöperating with said member whereby said means may be moved into locking position on an actuation of said operating-key.

70

18. A typewriter comprising in combination, a carriage, an operating-key, a line-lock stop carried by the carriage, connections moved by said stop into operative positions, and means controlled by said key for automatically locking the printing instrumentalities through said connections.

75

19. A typewriter comprising in combination, a carriage, operating-keys, a part adapted to translate and shift in different directions, carriage-controlled means for translating said part into a predetermined position, means controlled by an operating-key adapted to coact with said part when in such position to shift the same, and means 80 for locking the keys adapted to be moved by said part when shifted.

85

20. A typewriter comprising in combination, a carriage, a line-lock stop carried thereby, operating-keys, a lever actuated by 90 said line-lock stop, a line-lock adapted to be moved into locking position by said lever, and means controlled by an operating-key for moving said lever to bring said line-lock 95 into locking position.

95

21. A typewriter comprising in combination, a carriage, a line-lock stop carried thereby, a plurality of key-levers for printing characters composing a word, an operating-key adapted when actuated to space said carriage without printing any of said word-composing characters, a lever actuated by 100 said line-lock stop, a line-lock adapted to be moved into locking position by said lever, and means controlled by an operating-key 105 for locking said lock to prevent the key-levers from being actuated so as to cause said stop to move beyond said lever.

100

22. A typewriter comprising in combination, a carriage, operating-keys, a line-lock, 110 means intervening between said line-lock and an operating-key and normally disconnected from one of said parts, and means controlled by the movement of the carriage adapted to automatically establish connection between said disconnected parts, and thereby enable a movement of the operating-key to be transmitted to said line-lock.

115

23. A typewriter comprising in combination, a carriage, operating-keys, a line-lock 120 stop carried by the carriage, a line-locking device, a lever that coöperates at one end with the line-lock stop and at the other end with said line-locking device to move it in one direction, and means controlled by an operating-key for moving the locking-device through the instrumentalities of said lever.

125

24. A typewriter comprising in combination, a carriage, operating-keys, a line-lock operating-device movable by said carriage,

130

- 7
a line-lock movable into operative position by said operating-device, and means controlled by an operating-key for actuating said line-lock operating-device.
- 5 25. A typewriter comprising in combination, a carriage, operating-keys, a line-lock for locking said keys, means for actuating said line-lock adapted to be moved by the carriage, and means controlled by an operating key adapted to engage said first-mentioned means and actuate the same in such manner that the line-lock will be moved into effective position.
- 15 26. A typewriter comprising in combination, a carriage, a plurality of operating-keys, printing-mechanism connected with certain of said keys, a line-lock for impeding the movement of certain of said operating-keys to arrest the printing-mechanism, and means connected directly with an operating-key adapted to transmit a movement of said operating-key directly to said line-lock, whereby the latter may be shifted to locking position by the force moving an operating-key.
- 20 27. A typewriter comprising in combination, a carriage, type-keys, means for locking said type-keys coöperating directly with the carriage, a space-key, and independent means connecting said space-key with said first-mentioned means to enable the same to lock the type-keys upon an actuation of said space-key.
- 25 28. A typewriter comprising in combination, a carriage, a plurality of key-levers for printing characters composing a word, an operating-key adapted when actuated to space said carriage without printing, a line-lock, normally ineffective means for operating said line-lock adapted to be placed in operative position by the carriage when it occupies any one of the several successive stations beyond a predetermined point, and means for transmitting a movement of said operating key to said first-mentioned means when in operative position so as to cause the latter to lock the type-keys.
- 30 29. A typewriter comprising in combination, a carriage, type-keys, a non-printing space-key, a key-locking member normally ineffective during preliminary operations of the space-key, and means coöperating with said carriage, said member and said space-key only, for shifting said member into locking position through a movement of the space-key when the carriage has passed beyond a predetermined point of its travel.
- 35 30. A typewriting machine comprising in combination, a carriage, type-keys, a space-key, a normally ineffective line-lock for the type-keys, mechanism extending from said space-key to both the carriage and the lock, and a part provided upon the carriage for operating said mechanism at a predetermined station of the carriage travel, where-
- by upon actuating the space-key the latter will cause said lock to move into effective position.
31. A typewriting machine comprising in combination, type-keys, a space-key, a carriage, escapement-mechanism, and a line-lock mechanism independent of said escapement-mechanism, said line-lock mechanism being normally non-responsive to an actuation of said space-key, and normally incapable of being moved into locking position solely by the travel of the carriage, but adapted to be moved by the carriage when the latter reaches a predetermined point and thereby made responsive to an actuation of the space-key.
- 70 32. A typewriting machine comprising in combination, alphabetical and space-keys, a carriage, escapement-mechanism, a tappet adjustable in the direction of travel of the carriage, a locking member for said alphabetical-keys, and an actuating means for said locking member independent of said escapement-mechanism and operable partly by said tappet and by a space-key, whereby the latter may be enabled to directly operate said locking-member.
- 75 33. A typewriter comprising in combination, type key-levers, a space-key, a comb under the type key-levers for locking the same, a tappet upon the carriage, an arm movable by said tappet, a slide movable at its forward end in said comb, a bell-crank movable laterally by said slide when the latter is actuated by said tappet, and means for enabling said parts to coöperate to lock the type key-levers.
- 80 34. A typewriter comprising in combination, a carriage, type-keys, a space-key, a lock for said type-keys, and means for enabling a movement of the carriage to enable said space-key to force said lock into effective position.
- 85 35. A typewriter comprising in combination, a carriage, type-keys, a space-key, a lock movable by said space-key, and a normally ineffective interponent between said space-key and said lock and movable by said carriage into effective position.
- 90 36. A typewriter comprising in combination, a carriage, escapement-mechanism, type-keys, a space-key, and means independent of said escapement-mechanism for enabling the carriage and space-key to co-operate to lock the type-keys, said locking means being releasable at the will of the operator to permit the writing of additional letters.
- 95 37. A typewriter comprising in combination, a carriage, type-keys, a space-key, a member intermediate said carriage and space-key and movable by the carriage, and means for enabling the space-key to co-operate with said intermediate member to lock the type-keys, said locking means be-
- 100 105 110 115 120 125 130

ing releasable by a subsequent depression of the space-key to permit the writing of additional letters at the end of the line so long as the space-key is held down.

38. The combination in a typewriting machine of a traveling carriage, the printing instrumentalities, means for rendering the printing instrumentalities inoperative, the operation of which is determined by the position of the carriage, and a finger lever for actuating said means.

39. In a typewriting machine, in combination with the carriage of printing instrumentalities, locking means therefor, a plurality of levers, one of which is adapted to actuate locking means, and means carried

by the carriage which coöperates with the locking means at a predetermined position of the carriage.

40. In a typewriting machine, the combination of a carriage, line-locking mechanism, line-lock operating means, and means adapted at a predetermined point in the travel of the carriage to interpose an operative connection between the line-locking mechanism and its operating means.

Signed at New York, N. Y., this 5th day of September, 1905.

ALBERT F. NATHAN, JR.
